BENJAMIN BRENNER AND EMANUEL HASKELL, OF NEW YORK, N. Y.

DESIGN FOR A MODERNISTIC ANIMAL FORM FOR AUTOMOBILE RADIATOR FIXTURE,
DISPLAY OR ORNAMENTAL PURPOSES

Application filed January 8, 1931. Serial No. 38,249. Term of patent 14 years.

To all whom it may concern:

Be it known that we, BENJAMIN BRENNER and EMANUEL HASKELL, citizens of the United States, both residing at 1640 Ocean Avenue, in the county of Kings, city of New York, State of New York, have invented a new, original, and ornamental Design for a Modernistic Animal Form for Automobile Radiator Fixture, Display or Ornamental Purposes, the figures in the accompanying

drawing showing the plan side view, as shown by Figure 1, top view as shown by Figure 2 and front view as shown by Figure 3 of the animal form, showing our new design.

We claim:

The ornamental design for a modernistic animal form for automobile radiator fixture, display or ornamental purposes, as shown.

BENJAMIN BRENNER.
EMANUEL HASKELL.
